UNITED STATES PATENT OFFICE.

FRED MICHALICEK, OF PORTLAND, OREGON.

OPERATING MEANS FOR WASHING-MACHINES.

1,311,003.

Specification of Letters Patent.

Patented July 22, 1919.

Application filed May 3, 1917. Serial No. 166,173.

To all whom it may concern:

Be it known that I, FRED MICHALICEK, a citizen of the United States, and resident of Portland, in the county of Multnomah and

5 State of Oregon, have invented certain new and useful Improvements in Operating Means for Washing-Machines, of which the following is a specification.

10 This invention relates to washing machines and has more especial reference to an improved washing machine of the reciprocating plunger type.

15 The invention has for its dominant object to provide a washing machine having a reciprocal agitating plunger operable within the receptacle of the machine by novel mechanism for thoroughly circulating the cleansing solution through and between the matter being washed thereby.

20 Another important characteristic of the invention resides in the provision of a yieldable plunger operating connection whereby to allow slight relative movement of the plunger when the washing receptacle is

25 filled with matter to be cleansed.

30 The invention accordingly consists in the features of construction and arrangement of parts which will be exemplified in the construction hereinafter set forth, and the scope of the application of which will be indicated in the following claim.

In the drawings:

Figure 1 is a vertical section through the improved washing machine; and

35 Fig. 2 is a fragmentary detail and perspective of the connections between the reciprocal plunger operating means.

Similar characters of reference are employed in all of the above described views to indicate corresponding parts.

40 Referring now more specifically to the several figures of the said drawings a washing receptacle designated 1 is provided and is arranged upon a plurality of supporting legs 2. A cover member 3 is normally arranged over the open upper end of the washing receptacle and is provided with a concentric opening, which has a housing element 4 arranged thereover, the purpose of which

45 will be hereinafter more fully described. A perforate plunger 5 is mounted for reciprocation within the washing receptacle 1 and is connected to a rod 6, the upper end of which is formed to constitute a rack 7. A pinion 8 is rotatably mounted upon a stub shaft slidably mounted in a slot in the hous-

ing 4 and operated by a lever 8' and has fixedly connected thereto arms 9, the opposite extremities of which are detachably engaged with the yoke 10 slidable on the rod 60 11. An expansible coiled spring 14 is arranged about the outermost portion of the said rod 11 and has bearing upon a locking nut 15 turned into engagement with the screw threaded portion or end of the rod 11. 65

To one side of the washing receptacle 1 an operating handle or lever 12 is secured through the medium of a bracket 13 and has an opening formed adjacent the upper end of the same through which the adjacent portion of the rod 11 is passed.

70 Bearing brackets 16 are secured to the under face of the washing receptacle 1 and have rotatably mounted therein shafts carrying gears 17 and 18, it being noted that 75 the gear 17 is of a size greater than the gear 18. To the shaft carrying gear 18 a pulley 18' may be and preferably is secured and, obviously, permits the arranging of belt gearing thereabout whereby the machine 80 may be operated from a suitable source of power. If desired a balance wheel may be mounted on the opposite end of the shaft carrying the gear 18 for an obvious purpose.

85 A pitman 19 is pivotally engaged with the lower end of the operating handle 12 and with the gear 17 to allow the transmission of motion from the same by way of the operating handle to the reciprocal plunger working within the washing receptacle. 90

Within the washing receptacle 1 a perforate rack 20 having a plurality of legs 21 carrying pulleys upon their lower ends is arranged and is adapted to normally rest upon the bottom of the receptacle. A cable 95 22 secured to the upper portion of the washing receptacle is passed downwardly therein about the pulleys arranged upon the legs 21 and bent upwardly along the opposite side of the washing receptacle through a suitable 100 opening formed therein into engagement with a windlass 23 secured to the outer face of said receptacle. Obviously, by rotating the windlass through the medium of the handle attached thereto the cable will be 105 coiled thereabout and as a consequence, the rack 20 will be elevated within the receptacle to the desired extent.

110 In operation the handle 14 is rocked upon its pivot, thereby reciprocating the rod 11 and imparting oscillatory movement to the pinion 8, which by being in mesh with the

rack portion 7 of the plunger 5 will raise and lower the same, thus, thoroughly agitating the cleansing solution contained by the receptacle 1. When the clothes have been sufficiently washed the cover 3 is removed from the receptacle and the plunger 5 is moved to its uppermost position by sliding the gear 8 out of mesh with the rack portion 7 of the plunger rod 6. At this time 10 the yoke 10 may be disengaged from the arms 9 and uninterrupted removal of the cover 3 permitted. With the cover removed the windlass 23 is rotated thereby winding the cable 22 about the same and elevating the 15 perforate rack 20 in order that the clothes arranged on the same may be easily and readily removed therefrom.

Manifestly, the construction shown is capable of considerable modification and such 20 modification as is within the scope of my claim, I consider within the spirit of my invention.

I claim:

In a washing machine, a receptacle, a

plunger in said receptacle having the rod 25 thereof formed with a rack at its upper end, a cover for said receptacle, a housing arranged on said cover and communicating with an opening formed in the cover, said housing having slots formed in its side walls, 30 the rod of the plunger extending upwardly into the housing and through an opening formed in the top thereof whereby to maintain the same against lateral movement during sliding movement of the plunger, a segmental gear slidably and rotatably supported in said slots in the housing, a handle connected to said gear, an arm carried by the gear, an operating handle pivoted to one side of the receptacle and having detachable connection with said arm, and momentum increasing means secured to the lower portion of the receptacle and having connection with the lower end of said operating lever. 40

45 In testimony whereof I affix my signature hereto.

FRED MICHALICEK.
